STOKER CONTROL SYSTEM

Ernest T. Selig, Jr., Pittsburgh, Pa.

Application September 14, 1937, Serial No. 163,870

6 Claims. (Cl. 110—32)

This invention relates to a control system for automatic stokers, and the main object of the invention is to devise a control system which will substantially reduce and/or eliminate the blowing of ash from the stoker.

In domestic heating systems using coal as a fuel and employing automatic means for intermittently supplying fuel to the burner, the fuel burns down during the shut-down periods, leaving a ring of ash around the burner or tuyère, and, upon starting up again, the blower supplying air to the burner blows the ash out of the burner, and this ash, passing through cracks in the combustion chamber and smoke pipe, passes out into the room and becomes a source of considerable annoyance. The fine ash that is carried out of the furnace in the manner described, is commonly known as "fly ash."

According to my invention, I substantially eliminate the difficulty of "fly ash" by arranging the control system so that upon starting up after each shut-down period, the full blast of air is not supplied immediately upon starting of the fuel feed device, but means are provided to delay the application of the full blast of air for a time sufficient to allow the fuel feeding mechanism to feed enough coal to the burner to displace the ash from directly above the air nozzle or tuyère. In this manner, the fly-ash is removed from the direct path of the air blast supplied to the burner, and it drops down into the ashpit without being blown up into the combustion chamber.

In the forms of the invention disclosed herein, the delayed application of the full blast of air is controlled in accordance with temperature variations at a suitable point in or on the heating system.

A preferred embodiment of my invention, and several variations thereof, is illustrated in the accompanying drawing, in which:

Figure 1 is a diagrammatic view illustrating my invention applied to a coal-burning automatic stoker of a type commonly known;

Figure 2 illustrates a modified form of control in which the air is controlled by a damper in the blower outlet duct; and

Figure 3 illustrates a modified control system in which a heat-responsive expansible element controls a damper in the blower outlet by means of a Bowden wire.

Referring to Figure 1, a heating furnace of any suitable construction is indicated at 1, the furnace being provided with an ash-pit 1a, a combustion chamber 1b, and a flue 1c. A smoke pipe 2 connects the furnace with a chimney 3.

Arranged within the lower part of furnace 1 is a coal burner consisting of a tuyère 4 arranged within a casing 5 which constitutes an air chamber surrounding the tuyère 4. The blower 6, driven by a motor 7, supplies air to chamber 5 through a duct 6a. The motor 7 is also arranged to drive suitable mechanism for transferring coal from a supply bin 8 to the tuyère 4 through a conveyor duct 8a. This mechanism usually involves a rotary screw conveyor located in the duct 8a, although other types of conveyors may be used.

The motor 7, which drives the fuel feed mechanism and the blower 6, is energized from a suitable electric supply circuit indicated at 9, and the operation of the motor is controlled by a thermostatic switch 10 in accordance with the temperature or heat demands of the space in which the switch 10 is located. Thermostat 10 is usually but not necessarily located in one of 20 the first floor rooms. The motor 7 is preferably also energized at periodic intervals independently of the condition of the thermostat 10 by means of known control mechanism indicated at 11. This mechanism may assume various known 25 forms. One suitable arrangement is shown in patent to Gray, et al. 1,667,001. It should be understood that the automatic control 11 need not be employed, and the motor can be controlled directly by the thermostatic switch 10, if 30 desired.

The blower 6 is provided with an adjustable damper 6b arranged over the inlet port of the blower for controlling the amount of air supplied to the burner. The damper 6b is arranged to be 35 operated by a time-delay device which becomes effective a predetermined time after the motor 7 begins to operate. This time-delay device may assume various forms, but the device as shown in Figure 1 comprises a temperature-responsive 40 switch arranged at a convenient point in the heating system and controlling a suitable motive device for varying the amount of blast supplied by the blower 6. In the arrangement shown in Figure 1, the temperature-responsive switch 45 Af is located in the smoke pipe 2 and is responsive to the temperature of the gases passing through this pipe and is arranged to control the energizing circuit of an electromagnet 13, which in turn controls damper 6b through the rod 13a. 50 It will be understood that the switch Af is normally open for temperatures below a predetermined limit, and closes when the temperature rises above this limit.

In the operation of the arrangement shown in 55

Figure 1, the mechanism 11 will energize the motor 7 at periodic intervals of short duration so long as the space to be heated does not require any additional heat. This intermittent operation of the stoker is for the purpose of preventing the fire from dying out. As soon as the temperature of the space being heated falls below a definite limit, the thermostat 16 completes a circuit and causes operation of the stoker until the temperature in the space to be heated is brought back to normal. During the shut-down periods, the coal burns around the edge of the tuyère and leaves a ring of ash around the outer edge of the tuyère as indicated by the dotted area 4a in Figure 1, the hot spot of the fire 4b being located at the center of the tuyère. In the systems now commonly in use, the full blast of air is supplied to the air chamber 5 surrounding the tuyère 4 as soon as the motor 7 begins operation, and the ring of ash 4a is violently blown upwardly into the combustion chamber 1b, into the flue 1c and out the chimney 3. Some of the "fly-ash" filters through small cracks or openings around the doors of the furnace, or in the various joints, and is carried into other parts of the room. According to my invention, however, the damper 6b is normally set in a position such that the amount of air supplied to the air chamber 5 is insufficient to cause any substantial blowing of the fly-ash from around the rim of the burner. Accordingly, by arranging for sufficient time delay in the operation of electromagnet 13 after motor 7 begins to operate, the fuel feeding mechanism will supply enough coal to the tuyère to displace the ash from directly over the air openings in the tuyère by the time the damper 6b is fully open and the full blast becomes effective. As soon as the air openings in the tuyère become covered with unburned coal, the force of the air stream is thereby cut down and there is no substantial blowing of the fly-ash.

In Figure 1, a small amount of air is supplied to the burner as soon as the fuel feeding arrangement begins to operate. This air is sufficient to raise the temperature of the heating system, but at a slow rate. Since it will require some time for the switch A_f to operate, the full blast of air is delayed until after the fuel feed mechanism has supplied enough coal to the burner to displace the ash. The temperature-responsive device may be arranged in any number of different positions as shown in Fig. 1. For example, it may be arranged within the air chamber 5 adjacent to the tuyère 4 as shown at A_a, where it will be a thermostatic switch and will be responsive to the temperature of the tuyère or the temperature of the fuel bed. The switch may be arranged in the position A_b in Figure 1 where it will be responsive to the temperature within the combustion chamber, or at A_c where it will be responsive to the temperature of the walls of the combustion chamber. When located at A_d, the responsive element of the switch would extend into the water, steam or air space of the furnace or heating system and be responsive to temperature of the heating medium. In the position A_e, the switch would be responsive to the temperature of the flue gases, while at A_g it would respond to the temperature of the smoke pipe, and at A_h, the temperature responsive element being located in the chimney would be responsive to the temperature of the chimney gases.

Instead of controlling a damper on the inlet side of the blower 6, the temperature-responsive

switch may be arranged to control a damper 6c located in the outlet duct of the blower 6 as shown in Figure 2. The thermostatic switch indicated at A may be located in any of the various positions indicated above for Figure 1. In this arrangement, the damper 6c is normally set to permit a predetermined reduced blast of air to be supplied to the burner when the motor 7 is first energized, and when the thermostatic switch closes, the magnet 13 is energized to operate the damper 6c and thereby increase the blast to full blast.

Instead of using a thermostatic switch responsive to the temperature of a selected point in the heating system for controlling the damper 6c, I may employ a heat motor 15 of suitable design connected to the operating lever of the damper by means of a Bowden wire 15a as shown in Figure 3. The heat motor 15 may be arranged in any suitable position on the heating system to respond to an increase in temperature in substantially the same manner as described above for the temperature-responsive switch of Figure 1.

My invention not only reduces and/or substantially prevents the blowing of fly-ash, but it also improves the efficiency of operation of the burner. This latter advantage is realized by reason of the fact that the full blast of air is not applied at the beginning of each period of operation but is delayed until unburned coal covers all of the air openings in the tuyère. In this manner, the air blast is rendered completely effective for promoting combustion of the coal and none of the air is lost by passing through openings in the tuyère which are uncovered by reason of the ash having been blown away. Since there is no substantial amount of air wasted by passing through uncovered tuyère openings, the operation of the burner is more efficient, the temperature of the furnace rises quicker and each operating period is correspondingly reduced.

While I have described my invention as applied to a coal burning furnace, it will be understood that the invention may be applied to a coke burning furnace or to a furnace burning any other type of solid fuel.

What I claim is:

1. In combination, a furnace, a solid fuel burner for said furnace, means for supplying solid fuel to said burner, means for supplying a blast of air to said burner, automatic means for intermittently operating said fuel and air supply means, and means responsive to an increase in temperature of the combustion gases for increasing the amount of air supplied to said burner.

2. In combination, a heating system including a furnace, a solid fuel burner for said furnace, means for supplying solid fuel to said burner, means for supplying a blast of air to said burner, said air supply means being normally adjusted to supply less than the full blast of air, means for intermittently operating said fuel and air supply means in accordance with the heat demands of a space to be heated, and means located in the path of the combustion gases and being responsive to increase in temperature of said gases for increasing the air supplied by said means to full blast.

3. In combination, a furnace, a solid fuel burner for said furnace, means for supplying solid fuel to said burner, means for supplying a blast of air to said burner, means for intermittently operating said fuel and air supply means, a damper for normally restricting the amount of air supplied to said burner, electric

means for operating said damper, and a thermal switch having a temperature responsive element located in the direct path of the combustion gases and being responsive to increase in 5 temperature of said gases to energize said electric means and increase the amount of air supplied to said burner.

4. In combination, a heating system including a furnace, a solid fuel burner for said furnace, 10 means for supplying solid fuel to said burner, means for supplying a blast of air to said burner, said air supply means being normally adjusted to supply less than the full blast of air, means for intermittently operating said coal and air supply 15 means in accordance with the heat demands of a space to be heated, means for periodically operating said coal and air supply means independently of the condition of said space to be heated, and a heat motor responsive to the temperature of the combustion gases in said furnace for increasing the air supplied to said burner.

5. In combination, a solid fuel burner comprising a tuyère provided with air openings therein, 20 means for supplying solid fuel to said burner to cover said openings, means for supplying a blast of air through said openings, means for intermittently operating said coal and air supply 25 means, whereby during the shut-down periods

the fuel burns out above certain of said openings, means operative upon each starting of said fuel and air supply means for restricting the amount of air supplied to said burner while said fuel feeding means supplies sufficient fuel to said burner to displace the ash from above the air openings in said burner, and means located in the direct path of the combustion gases in said furnace and being responsive to increase in the 5 temperature of said gases for increasing the 10 amount of the air supplied to said burner.

6. In combination, a heating system including a furnace, a solid fuel burner for said furnace, 15 means for supplying solid fuel to said burner, means for supplying a blast of air to said burner, said air supply means being normally adjusted to supply less than the full blast of air, means for intermittently operating said coal and air supply 20 means in accordance with the heat demands of a space to be heated, means for periodically operating said coal and air supply means independently of the condition of said space to be heated, means responsive to the 25 temperature of a portion of said heating system heated by said burner, and being operative upon increase of temperature thereof for increasing the amount of air supplied to said burner.
